UNITED STATES PATENT OFFICE.

WILLIAM DANIEL HUFF, OF LA FAYETTE, LOUISIANA, ASSIGNOR OF ONE-HALF TO
JAMES J. CONNOLLY, OF ROANOKE, VIRGINIA.

ELECTRICALLY-HEATED CULINARY UTENSIL.

1,368,152.

Specification of Letters Patent.

Patented Feb. 8, 1921.

Application filed July 3, 1919. Serial No. 308,351.

To all whom it may concern:

Be it known that I, WILLIAM DANIEL HUFF, a citizen of the United States, residing at La Fayette, in the parish of La Fayette and State of Louisiana, have invented certain new and useful Improvements in Electrically-Heated Culinary Utensils; and I do hereby declare the following to be a full, clear, and exact description of the invention, such as will enable others skilled in the art to which it appertains to make and use the same.

My present invention relates to improvements in electrically heated culinary utensils, and it is intended to provide an arrangement by means of which a minimum amount of electricity may be used to accomplish the desired heating result, and in which also the heat generated will be almost entirely concentrated in a comparatively small region, thus avoiding any disagreeable heating of the surrounding atmosphere, and causing inconvenience or discomfort to the attendants, as well as avoiding any unnecessary loss of heat.

The invention is intended to be used in kitchens, pantries, or other convenient places where the cooking or heating is to be done, and a plurality of such arrangements might be provided adjacent to the ordinary kitchen range or cook stove, and thus may be used in place of or supplemental to the ordinary cooking apparatus now in use.

My invention will be more fully understood after reference to the accompanying drawings, in which like parts are indicated by similar reference symbols throughout the several views, and in which:

Figure 1 shows three of the devices mounted in a framework, and constituting an electric range.

Fig. 2 is a front elevation on a larger scale of one of the devices.

Fig. 3 shows a central vertical section through the device shown in Fig. 2, but with the electrical connections and other electrical parts omitted.

Fig. 4 shows a view of the electric switch and connections, with the top of the case removed.

Fig. 5 shows a section along the line 5-5 of Fig. 4, and looking in the direction of the arrows.

Fig. 6 shows a section along the line 6-6

of Fig. 2, the parts being shown on a larger scale than in Fig. 2.

Fig. 7 is a plan view of the electric heating coils shown in Fig. 6.

Fig. 8 shows a section along the line 8-8 of Fig. 7, and looking in the direction of the arrows.

Fig. 9 is an inverted plan view of the insulating piece to which the heating coils are connected.

Fig. 10 is a sectional elevation showing the central connection common to all the heating coils.

Fig. 11 is a similar view to Fig. 10, but shows the connection at the opposite end of one of the heating coils.

Fig. 12 shows a section through one of the heating coils, and shows the inclosing tube and the insulating material surrounding the wire; and

Fig. 13 is a top plan view of the insulating plug to which the various heating coils are connected.

A represents any suitable framework, having suitable shelves *a* and *a'*, and an angle iron *A'* which serves as a support for the heating retorts *B*, which are preferably constructed hollowed out, as at *B'*, in Fig. 3, and from this hollowed out portion the air is preferably exhausted so as to lessen the conducting power of the walls of the chamber and retain the heat therein.

The retorts *B* may be made of metal, glass, or other suitable material, but preferably of flint or pyrex glass, having the walls of the vacuum chamber silvered as is well known in the manufacture of thermos bottles.

The bottom of the retort is perforated, as at *B'*, to receive the insulating plug which will be hereinafter described.

C represents the container in which the article to be cooked or to be heated is placed, and this is preferably provided with a flange *c* having the asbestos gasket *c'* to fit on the annular edge *b* of the top of the heating chamber *B*, as shown in Fig. 3.

D represents a plug made of insulating material, flanged, as at *d*, to fit in the opening *B'* in the bottom of the heating chamber *B*, and mounted above this plug is an insulating strip *E* which carries the series of heating coils.

I have shown three of such coils *F*, *F'* and

F^2 , but the number may be increased or decreased as desired. These coils are preferably formed of an inclosing tube f , containing a series of annular disks or beads f' of 5 glass or other suitable material, through which fine heating wire f^2 passes, the ends of this wire f^2 being connected to the larger wire G , which is in turn connected to the 10 conducting strip H secured beneath the insulating piece E .

This strip H is connected to the central contact H' , which projects down into a metal tube I in the insulating plug D . The inner ends of each of the coils F , F' and F^2 15 are connected to a corresponding contact K , by means of the rods G' , see Fig. 10, and the closed end f^o of the tubes, which projects down into the tubes I' in the insulating plug D . The lower ends of these tubes are 20 connected by the conductors L to the three pairs of superposed contact segments M of the switch arrangement shown in Figs. 4 and 5, which contacts are insulated from each other.

25 Projecting up into the tube I is the conducting post N , which carries the switch arm P , which arm comprises a spring member p and a contact plate p' , notched as at p^o to engage one or the other of the spring holders Q , Q' , Q^2 and Q^3 . This post N also carries the lever arm R , preferably having a portion thereof made of insulating material, as at R' , and carrying an indicator r which passes over the front of the heating chamber, and the position of said indicator shows the position of the switch, or the number of heating units in circuit.

30 The current is shown as carried in by the conductor S , and is carried off or grounded 40 by the conductor S' , as shown in Fig. 4.

In Fig. 2 I have shown the current cut out entirely, the indicator r being to the left of the markings 1, 2 and 3, which correspond to the positions of the lock springs 45 Q , Q' , Q^2 and Q^3 .

In Fig. 4 I have shown one of the heating coils in circuit, the switch lever being shown in full lines, while the switch lever as indicated in dotted lines shows the position of 50 the same when the electricity is cut out, as indicated in Fig. 2.

By turning the switch lever over to the right from the position shown in Fig. 4, I may cut in two or three of the heating 55 coils, and again by swinging the lever to the left these heating coils may be cut out *seriatim*.

The switch mechanism herein described is what is known as a "snap switch," and 60 operates as follows:—

The central pin N has rigidly attached thereto the yoke T , with the two arms t and t' , and when the switch lever is turned to the right, as in Fig. 4, the arm t will press 65 the arm p , causing the plate p' to snap out

of engagement with one of the springs Q , Q' , or the like. The resiliency of the arm p will cause the plate p' to snap into engagement with the next spring Q^2 .

In turning the switch lever in the reverse 70 direction, a similar action will be effected by the arm t' of the yoke T .

The various parts of the switch mechanism are inclosed in a box or casing W , having a bottom w made of insulating material, 75 which casing may be secured to the angle iron A' by means of the screws w' .

The electric circuit to the various utensils is controlled by a switch X , shown in 80 Fig. 1.

It will be noted that the gasket c' of the container C will make a substantially air-tight joint at the top of the heating chamber, thus imprisoning the heated air in said chamber, and preventing the escape of same 85 should the pressure become excessive, in which case the container will lift slightly, permitting the excess pressure of the air to be released; or the leakage of the air from the interior of the heating chamber may 90 prevent any possibility of excess air pressure in the system.

By having very fine heating wire 95 inclosed in curved tubes, a comparatively short heating wire may be used, and yet a high temperature may be secured, and by having this wire contained in an inert medium, such as nitrogen, it is not likely to become burnt out.

If it be desired to clean the heater at any 100 time, it will be a simple matter to lift up the insulating strip E , and the parts carried thereby, and remove the heating coils from the heating chamber, and the same may be cleaned or repaired and replaced, if desired.

In the same way, the plug D may be lifted 105 out of its socket, and also the switch box W may be removed by disengaging the screws w' .

It will be seen that the device may be 110 cheaply constructed, and the parts may be made inter-changeable and duplicates substituted should they become worn or injured in any way.

It will be seen that the heating chambers 115 are located and constructed so that they may be readily cleaned, either in place, or after being removed.

The heating element is shown as inclosed in a metal tube bent in a curved or spiral 120 form, so that the resiliency of the tube will allow the coil to expand or contract without injuring the apparatus.

In order to prevent oxidization of the fine wire contained in the heating coil, I 125 preferably exhaust the air from the tubes containing the heating members and fill up the vacuum thus created with nitrogen or some other inert gas, preferably nitrogen as this may be so readily secured.

By having the heating wire very fine and inclosed in glass disks or beads, and contained in a non-oxidizing medium, it is not likely to wear out or burn out, and thus the 5 heater will last a long time without the necessity for replacing the parts.

It will be obvious that various modifications might be made in the herein described apparatus and in the construction, combination 10 and arrangement of parts which could be used without departing from the spirit of my invention.

Having thus described my invention, what I claim and desire to secure by Letters Patent 15 of the United States is:—

1. Apparatus of the character described, comprising a cylindrical receptacle having double side and bottom walls spaced apart, and the double bottom walls formed with a 20 cylindrical passage therethrough, the air being exhausted from the space between the said double walls, an insulating plug with electrical conductors carried thereby removably mounted in said passage in said bottom 25 walls, an insulating support carried by said plug at its upper end, a heating coil carried by said support, and means for completing an electric circuit through said conductors and through said coil, substantially 30 as described.

2. Apparatus of the character described, comprising a cylindrical receptacle having double side and bottom walls spaced apart, and the double bottom walls formed with a 35 cylindrical passage therethrough, the air being exhausted from the space between the said double walls, an insulating plug with electrical conductors carried thereby removably mounted in said passage in said bottom 40 walls, an insulating support carried by said plug at its upper end, a plurality of heating coils carried by said support, and means for completing electric circuits *seriatim* through said coils, substantially as 45 described.

3. Apparatus of the character described, comprising a cylindrical receptacle having double side and bottom walls spaced apart, the top of said double side walls being joined together to form a narrow rounded 50 annular edge, and the double bottom walls formed with a cylindrical passage therethrough, the air being exhausted from the space between the said double walls, an insulating plug with electrical conductors carried thereby removably mounted in said passage in said bottom walls, an insulating support carried by said plug at its upper 55 end, a heating coil carried by said support, and means for completing an electric circuit through said conductors and through said coil, with a hollow cooking utensil adapted to project into said receptacle and provided with a flange adapted to fit snugly on said annular edge and to form a removable cover 60 for said receptacle, substantially as described.

4. Apparatus of the character described, comprising a cylindrical receptacle having double side and bottom walls spaced apart, 70 the top of said double side walls being joined together to form a narrow rounded annular edge, and the double bottom walls formed with a cylindrical passage therethrough, the air being exhausted from the 75 space between the said double walls, an insulating plug with electrical conductors carried thereby removably mounted in said passage in said bottom walls, an insulating support carried by said plug at its upper 80 end, a plurality of heating coils carried by said support, and means for completing electric circuits *seriatim* through said coils, with a hollow cooking utensil adapted to project into said receptacle and provided with a 85 flange adapted to fit snugly on said annular edge and to form a removable cover for said receptacle, substantially as described.

WILLIAM DANIEL HUFF.
